UNITED STATES PATENT OFFICE

HARRY I. LAHR AND LEHMAN D. HELWIG, OF WADSWORTH, OHIO, ASSIGNEES TO THE
OHIO MATCH COMPANY, OF WADSWORTH, OHIO, A CORPORATION OF OHIO

ELEVATOR OR TRANSFER DEVICE

Application filed March 10, 1925. Serial No. 14,495.

This invention relates to an elevator or transfer device, for receiving articles or packages at one level, and elevating or transferring them to another level and there discharging them.

The object of the invention is to provide a device of the character above described which is capable of continuous operation and which is provided with auxiliaries adapted to ensure its operation without failing and hence without interruption while it is in service.

The device as shown in the drawing, and as hereinafter described, is designed particularly for the handling of boxes of matches whereby such boxes of matches may be received at one level, from a match boxing machine, and elevated and discharged at another level onto a travelling conveyor or the like, for distribution or transportation to a point at which they may be subjected to some further operation such as wrapping them in the ordinary commercial packages.

Although the invention is, as stated, designed particularly for the above use, it will be obvious that its utility is not confined thereto, but that it may be equally useful and efficient in handling articles or packages other than boxes of matches, and the invention is to be so construed.

The invention consists in an elevator or transfer device, including a substantially vertically arranged conveyor chain or belt provided at intervals throughout its length with lugs to receive and elevate boxes of matches or other articles, provision being made of mechanism for feeding the articles to be elevated or transferred to the upwardly travelling or working flight of the conveyor chain or belt adjacent to its lower end, and there being provided also adjacent to the upper end of the conveyor chain or belt means for automatically intermittently discharging the boxes of matches or other articles elevated by the chain or belt, means being associated with the discharge mechanism for preventing discharge of the boxes of matches or articles in improper position, as we will proceed now to explain and finally claim.

In the accompanying drawings illustrating the invention, in the several figures of

which like parts are similarly designated, Figure 1 is a side elevation illustrating the device of the invention. Fig. 2 is a section on a larger scale, taken on the line 2—2 of Fig. 1 and looking in the direction of the arrows. Fig. 3 is a section on a larger scale taken on the line 3—3 of Fig. 1 and looking in the direction of the arrows. Fig. 4 is a sectional elevation taken on the line 4—4 of Fig. 2 and illustrating the mechanism located adjacent to the lower end of the conveyor chain for depositing the boxes of matches or other articles thereon. Fig. 5 is a fragmentary detail view, in sectional elevation, showing the mechanism for automatically discharging the boxes of matches or other articles from the device. Fig. 6 is a fragmentary detail sectional view of the tipper mechanism for ensuring proper positioning of the boxes of matches or other articles just prior to their discharge from the discharge device. Fig. 7 is a fragmentary detail sectional view of one of the trip members for ensuring proper positioning of the boxes of matches or other articles upon the conveyor chain or belt during their upward progress therewith.

Referring more particularly to the drawings, 1 indicates one member of an ordinary pipe framework for supporting a travelling conveyor 2, such as that shown in the co-pending application of Harry I. Lahr and Orlo E. Swartz, filed November 8, 1924, Serial No. 748,758, and upon this member 1 is mounted a bracket 3 carrying a stand 4 in which is carried a shaft 5 on which is journaled a double sprocket 6 over which run two similar conveyor chains 7 spaced apart an appropriate distance, as determined by the spacing of the two sprockets of the double sprocket, to accommodate the articles which the device is designed to handle. Spanning these two chains at suitable intervals throughout their length is a plurality of lugs 8 of such shape and size as to conveniently accommodate the articles to be handled. These chains 7 extend downwardly to a double sprocket 9 similar to the sprocket 6 and pass around this sprocket, thereby forming a working flight *a* and an idle flight *b* of the conveyor chain.

The double sprocket 9 is mounted upon a shaft 10 journalled in suitable bearings 11 carried by brackets 12 appropriately mounted as at 13 upon an extension 14 or the like 5 of, or in proximity to, the match boxing attachment of a match machine. Suitable chain and sprocket gearing 10' imparts motion to shaft 10 and to the sprocket 9 and chains 7. The brackets 12 carry also a guide member 15 10 comprising a pair of similar flanged tracks 16 which extend downwardly adjacent to the sprocket 9 and are adapted to guide the boxes of matches into position to be engaged by the lugs 8 of the chains 7. Abutting against and 15 co-operating with the guide member 15 are ways 17 onto which the boxes of matches are fed from the match boxing machine, and along which they are successively advanced by their own step-by-step feed motion as they 20 are discharged from the match boxing machine.

In order to prevent boxes of matches from sliding forward too rapidly, and thus prevent them from being introduced out of time 25 to the lugs 8 of the conveyor chains 7, we provide a friction hold-down member 18, same being in the nature of a weight adapted to exert sufficient pressure upon the boxes of matches to prevent their untimely advance, 30 this member 18 being pivoted at 19 upon an extension 20 of one of the brackets 12.

The working flight *a* of the conveyor chains runs in a guideway 21 composed of a plurality of suitably spaced and arranged 35 rods 22 which form, in effect, a chute for the reception of the boxes of matches, whereby the boxes may be held in proper transverse alignment during their upward travel.

Pivoted in suitable bearing members 23 40 carried by the guideway 21 are arms 24 carrying trip members 25. The function of these members will be set forth in connection with the description of the operation of the device.

The guideway 21, at its upper end follows in contour for a short distance the bend taken by the conveyor chains 7, as they pass over the double pulley 6 and then extends horizontally for a short distance as at 26, and at this 50 point, there is arranged a tipper member comprising a plate 27 pivoted at 28 and carrying a weighted arm 29, this arm being provided with a lug 30 arranged to strike against a stop 31 to limit the movement of the plate 55 27 in one direction. Then the guideway makes a downward turn as at 32 at a slight incline and is closed to form for a short distance what is in effect a tube, by the addition of other rods 37 carried by a bracket 34 suitably attached to the stand 4. For ensuring 60 proper discharge of the boxes of matches at regular intervals from the discharge end *c* of the guideway, we provide a discharge mechanism or trap (Fig. 5) comprising a 65 shutter member or plate 35 carried by a bell

crank lever 36 pivoted at 37 in suitable bearings 38 mounted upon the guideway, and having connected with it a toggle, composed of a link 39 and trip lever 40, the trip lever 40 having a fixed pivot 41 on a bearing member 42 mounted upon the guideway. The free end 43 of the trip lever 40 extends into the path of travel of the lugs 8 of the conveyor chains 7 as they pass over the pulley 6 and start their descent, and consequently, as each lug strikes the trip lever 40, it will cause the shutter plate 35 to be withdrawn from the position illustrated in Figs. 1 and 5 and out of box intercepting relation to the guideway 21, and will allow a box of matches, if one is resting upon it, to be dropped upon the conveyor 2. The shutter plate 35 is held normally in the position shown in Figs. 1 and 5 by means of a spring 44, and its movement under the influence of the spring 44 is limited by means of a bar 45 carried by the guideway. 75 80 85

The operation of the device is as follows:— As hereinbefore explained, the boxes of matches advance step by step along the ways 17 as they are intermittently fed onto same 90 from the discharge end of the boxing machine, and as they pass under the friction device 18 will drop one by one down the guide member 15 between its flange tracks 16 and will be in position to be engaged by the upwardly travelling lugs 8 of the working flight *a* of the conveyor chains. 95

The lugs 8 are so arranged upon the conveyor chains 7 and will pass the point of introduction to the conveyor chains of the boxes of matches at such intervals that only every alternate one of the lugs, rather than each of same, will receive a box of matches. This is done for the reason that it is customary, while the boxes of matches are passing along the 100 ways 17, for an inspector to lift out a box of matches from time to time to see that it is properly filled, and to make such other inspection of it as may be necessary, and obviously, when the inspector replaces the box 105 of matches which he has just inspected in the advancing row of boxes, he throws the row, so far as its feed to the conveyor chains is concerned, out of time with relation thereto, thereby feeding two boxes of matches to the chain when one box only would normally be fed thereto. The intermediate lug 8 will 110 take care of this extra box of matches. 115

As the boxes of matches ascend the elevator guided by the guideway 21 under the influence of the lugs 8, it sometimes happens that boxes assume the position upon the lugs indicated at *d*. This position is incorrect, and in order that the boxes thus positioned may be repositioned properly, as indicated at *e*, I provide 120 the trip members 25. These trip members are so arranged as to have their lower edges *f* engage with the outstanding side of a box of matches when it is in the position indicated at *d* and will tend to turn the box of matches 125 130

over with the end *g* of the lug 8 upon which it rests as a fulcrum, but this turning will not be completed until the box of matches is well within the trip member 25, and as the box of matches falls off of the lug 8 on which it was resting, it will be guided by the trip member 25 so as to fall upon the next lug 8 following, which, ordinarily, carries no box of matches.

As many of these trip members may be employed as desired, or they may be omitted entirely if it is deemed advisable, and righting of the boxes with relation to the conveyor chains may be entrusted entirely to the tipper member including plate 27 arranged adjacent to the discharge end of the device. This tipper member is so arranged that if a box of matches advances in the position indicated at *d*, the box will strike against the plate 27 (Fig. 6), and will be turned over as it is advanced in the guideway.

As the boxes of matches pass under the tipper member, they will slide down one by one against the shutter member 35 and will be automatically and intermittently discharged thereby onto the conveyor 2.

The discharge mechanism including the shutter member 35 is used in combination with the device of the invention for the reason that in some instances, it has been found that boxes of matches making the drop from the horizontal portion 26 of the guideway through the inclined portion 32 thereof and thence downwardly upon the conveyor 2 when no device similar to the discharge mechanism or trap is used, will attain sufficient momentum to cause them to bounce upon striking the conveyor 2 and assume positions thereupon other than that which it is desired that they assume. With the discharge mechanism or trap in use, the drop of the boxes of matches is broken at a point near the conveyor 2, and when they are released upon movement of the shutter member 35, they have only a short distance to fall to reach the conveyor, and this short distance has been found to prevent their acquiring sufficient momentum to bounce or otherwise get out of alignment upon striking the conveyor.

As the boxes are deposited upon the conveyor 2, they will be carried along thereby and out of the guideway, thus making room for other boxes of matches subsequently discharged from the elevator.

It will thus be seen that we provide a very simple and efficient mechanism well adapted for the purpose for which it is designed, and provided with auxiliaries to correct faulty positioning of boxes of matches during their transfer by it and to prevent misalignment or incorrect positioning of the boxes when discharged. Moreover, the device is so designed, and operates in such a manner as to practically eliminate the possibility of its failure to function properly, and is of suf-

ficiently rugged construction not to become inoperative due to breakage.

Various changes are contemplated as within the spirit of the invention and the scope of the following claims.

What we claim is:—

1. In a transfer device, a travelling conveyor chain provided with means for receiving articles thereon, means for feeding articles to be transferred to said chain, means for guiding said articles during their transfer, and means for discharging said articles from said guiding means including a trap and means connected therewith and intermittently actuated by said chain for discharging said articles in timed relation to the travel of said chain. 70

2. In a transfer device, a travelling conveyor chain provided with a plurality of spaced article-receiving lugs, said articles being so fed in timed relation to the travel of said chain that each alternate lug only receives an article, means for ensuring proper positioning of said articles on said lugs including trip members arranged to rotate an incorrectly positioned article and cause it to fall upon the next succeeding lug in proper position, and a discharge mechanism for discharging said articles from the transfer device in timed relation to the travel of said chain. 85

3. In a transfer device, a travelling conveyor chain having a working flight and an idle flight provided with a plurality of spaced article-receiving lugs, means for feeding articles to the lugs of said chain, a guideway for guiding the working flight of said chain and the articles carried by the lugs thereof, said guideway having a discharge end, and discharge mechanism arranged in said discharge end and including a trap and means connected with said trap and actuated by said chain lugs for discharging articles therefrom in timed relation to the travel of said chain. 100

4. In a transfer device, a travelling conveyor chain having a working flight and an idle flight, sprockets over which said chain runs, one of said sprockets being at a higher level than the other, a guideway paralleling the working flight of said chain and extending from the level of the lower sprocket to the level of the higher sprocket, a bend in said guideway adjacent to said higher sprocket, said guideway provided with a discharge end at a downward incline adjacent to said bend, means for feeding articles to be elevated to the working flight of said chain, a tipper member arranged adjacent to the bend of said guideway near its discharge end and adapted to correctly position in said guideway articles incorrectly positioned therein prior to their discharge, discharge means arranged in the discharge end of said guideway and including a shutter member 115 120 125 130

adapted to arrest movement of the articles in the downward incline of said guideway, and means for actuating said shutter member to discharge articles arrested thereby in timed relation to the travel of said conveyor chain.

In testimony whereof we have hereunto set our hands this 9th day of March, A. D. 1925.

HARRY I. LAHR.
LEHMAN D. HELWIG.
